CLAIM

We claim the ornamental design for a roller compactor machine, substantially as shown and described.

DESCRIPTION

FIG. 1 is a perspective view of the roller compactor machine, according to the present invention.

FIG. 2 is a front elevation view of the machine.

FIG. 3 is a left side elevation view of the machine.

FIG. 4 is a right side elevation view of the machine; and, FIG. 5 is a top plan view of the machine.

The broken lines shown depict portions of the compact vibration actuator which form no part of the claimed design.
